UNITED STATES PATENT OFFICE.

HIPPOLYTE W. ROMANOFF, OF NEW YORK, N. Y.

METHOD OF PREPARING PARQUET FLOORING OR WAINGSCOTING.

Application filed August 2, 1923. Serial No. 655,375.

To all whom it may concern:

Be it known that I, HIPPOLYTE W. ROMANOFF, a citizen of Russia, residing at New York, county of New York, and State of New York, have invented certain new and useful Improvements in Methods of Preparing Parquet Flooring or Wainscoting, of which the following is a specification.

The present invention relates to improvements in methods of preparing parquet flooring or wainscoting, etc., and it is the principal object of my invention to provide a novel method for cheaply and quickly preparing parquet flooring of any suitable material, size and shape.

A further object of my invention is the provision of a novel method of laying parquet flooring consisting of an inexpensive base and a top plate affixed to the base and cut in such a manner that the corners of the flooring plates on one base strip snugly fit into the corresponding spaces between two plates on the adjoining strip.

These and other objects of my invention will become more fully known as the description thereof proceeds, and will then be more specifically pointed out in the appended claims.

In the accompanying drawing forming a material part of this disclosure:

Figure 1 shows a stencil in plan view adapted to be used in connection with the practical execution of my process.

Figure 2 is a section on line 2—2 of Figure 1.

Figure 3 is a top plan view of a bottom or base plate provided with an adhesive material or glue passed through the stencil.

Figure 4 is a fragmentary top plan view of a top plate adapted to be glued to said base, showing in dotted lines the cut base plate.

Figure 5 is an end view thereof.

Figure 6 is a top plan view of a strip of the base carrying a part of the parquet flooring separated from its mate.

Figure 7 is a side elevation thereof.

The stencil 10, preferably of metal is provided with a plurality of hexagonal openings 11 having bevelled edges.

A special brush machine is employed to apply glue through openings 11 onto a base plate 12, so that the glued places have the shape as illustrated at 13. A top plate 14 is pressed by a special machine upon the flooring, and base plate 12 and top plate 14

are then cut, the former into strips 16 and the latter into blocks 15. The strips 16 provide supports to which the parquet flooring 14 is adhering in the manner best illustrated in Figure 6, allowing a nailing of the strips 16 to the floor or wainscot as at 17 with the next strip in such a proximity that the apexes of the flooring squares 14 of one row engage the triangular space between two squares of the other row.

From the above description the practical execution of my novel process or method will be quite clear.

The base plate 12 prepared as described presents a series of spaced adhesive areas, and following the application of the top plate 14 thereto, a connection between such bottom plate and top plate will be secured through these adhesive areas. The top plate and bottom plate are then independently cut, the top plate being divided along uniform longitudinal and transverse divisions to form separate, and in the instance shown, rectangular blocks 15. The bottom plate is cut on lines substantially diagonal to the cuts of the top plate, and these diagonal cuts of the bottom plate are such as to leave strips 16 on which appear the spaced adhesive areas 13, those portions of the bottom plate between the margins of the adhesive areas thus defined being entirely removed. When completed, the respective blocks of the top plate will be supported on diagonally arranged bottom strips, any one such strip having arranged thereon a series of immediately adjacent blocks having their diagonals aligned longitudinally of the strip. Thus the width of the strip underlying the meeting points of adjacent blocks presents an area between and wholly free of the meeting edges of adjacent blocks to facilitate the insertion of the securing nails in applying the flooring. The securing means indicated at 17 will thus effectively secure the flooring in place without in any way passing through the flooring section proper, that is, the upper plate 14. Furthermore, by this arrangement, the interfitting of the next set of blocks will cause said blocks to overlie and conceal the securing means 17 of the previous set.

Having thus described my invention, what I claim as new, and desire to protect by Letters Patent is—

1. A method of preparing parquet flooring or wainscoting consisting in providing

a base plate with glue engaging a top plate therewith, cutting each plate separately, and securing said cut base plate to a floor in such a manner that an uninterrupted parquet floor is formed by the top plate.

2. A method of preparing parquet flooring or wainscoting consisting in pressing glue through a stencil with hexagonal openings against a base plate, placing a top plate 10 on said glued plate, cutting both plates into a plurality of sections of desired shape.

3. A method of preparing parquet flooring or wainscoting consisting in brushing glue through a stencil having a plurality of 15 openings provided with bevelled edges upon a base plate, placing a top plate on said base

plate, and cutting both plates into a plurality of parts.

4. A method of preparing parquet flooring, consisting in providing a base and 20 forming a plurality of independent adhesive areas on said base, securing a parquet flooring section to the adhesive areas of the base by pressure, dividing the parquet flooring section into blocks of desired outline, dividing 25 the base into strips, each including a plurality of such adhesive areas and thereby supporting a plurality of blocks of the flooring section.

In testimony whereof I have affixed my 30 signature.

HIPPOLYTE W. ROMANOFF.
